G. H. PIGGOT

DOOR AND LOCKING MEANS THEREFOR

Filed May 28, 1923

UNITED STATES PATENT OFFICE.

GRAHAM H. PIGGOT, OF CHICAGO, ILLINOIS, ASSIGNOR TO FEDERAL STEEL FIXTURE COMPANY, OF CHICAGO, ILLINOIS, A CORPORATION OF ILLINOIS.

DOOR AND LOCKING MEANS THEREFOR.

Application filed May 28, 1923. Serial No. 641,846.

This invention relates to locker doors, and more particularly to the doors of steel lockers, and the invention relates especially to the means for latching or locking the door in closed position.

Generally stated, the object of the invention is to provide an improved construction and arrangement whereby the locking means will operate in an easy and comparatively quiet manner.

It is also an object to provide an improved construction and arrangement whereby the locking means, which operate by gravity to lock the door, may be controlled by the rotational movement of the hand, instead of by an upward movement or lift, in order to unlock the door.

Another object is to provide an improved construction and arrangement whereby the sheet metal door will be light and strong, and of less weight than has been the case with some structures heretofore employed for this purpose.

It is also an object to provide certain details and features of construction and combinations tending to increase the general efficiency and the desirability of a locker and locking means of this particular character.

To the foregoing and other useful ends, the invention consists in the matters hereinafter set forth and claimed; and shown in the accompanying drawings, in which,

Fig. 1 is a front elevation of a steel locker embodying the principles of the invention.

Fig. 2 is an enlarged vertical section on line 2—2 in Fig. 1.

Fig. 3 is a vertical section on line 3—3 in Fig. 2.

Fig. 4 is a horizontal section on line 4—4 in Fig. 3.

As thus illustrated, the locker may be of any suitable form and size, and as shown comprises a body 1, to which the door 2 is hinged at 3 in any suitable manner. The door at the other side of the locker has a rotary handle 4 by which the door is unlocked and opened.

As shown more clearly in Fig. 4, said door is constructed of sheet metal and has a vertical front wall 5 provided at each edge with hollow reinforcing portions formed by bending the metal back to pro-

vide side walls 6 and inner oblique walls 7, so that these hollow stiffening portions are triangular in horizontal cross section. This reduces the amount of metal employed and reduces the weight, and at the same time insures a strong and rigid construction.

The locking means comprise a vertically disposed section of angle iron 8 arranged to slide up and down between the walls 6 and 7 adjacent the handle 4 previously mentioned. This section of angle iron fits fairly snugly in the housing thus provided by the sheet metal walls of the door, and is pro-

vided with extensions 9 which work in vertical slots 10 to permit the up and down motion of the locking means. The casing 11 is provided with double angle strike pieces 12 having vertical slots 12 therein to re-

ceive the hook-shaped latching portions 9, and the portions 9 have beveled edges 120 to engage the lower ends of the slots 12, so that when the door is closed, the angle iron 8 is raised until the portion 9 slides through the slot 12 of the strike piece 11, and then the notches 13 of the portions 9 permit the angle iron 8 to drop down until the hook-shaped por-

tion 9 is in locking position, as shown in Figs. 2 and 3, thus holding the door in closed position. It will be understood that the accompanying drawings, in which,—

Fig. 1 is a front elevation of a steel locker embodying the principles of the invention.

Fig. 2 is an enlarged vertical section on line 2—2 in Fig. 1.

Fig. 3 is a vertical section on line 3—3 in Fig. 2.

Fig. 4 is a horizontal section on line 4—4 in Fig. 3.

As thus illustrated, the locker may be from the strike pieces 11, comprise a lug 14 on the inner surface of the locking bar 8, and an arm 15 having a notch 16 shaped to engage the lug 14, as shown in Fig. 3, door at the other side of the locker has a said arm 15 being rigid with the inner end portion 17 of the handle 4 previously mentioned. This handle is rotatably mounted on the door, and when the handle is twisted or rotated the arm 15 will press upwardly against the lug 14, and this will move the door.

As shown more clearly in Fig. 4, said door is constructed of sheet metal and has a vertical front wall 5 provided at each edge with hollow reinforcing portions formed by bending the metal back to pro-

Of course, when the door is closed, the latching means operate by gravity in the manner explained. But when the door is unlocked, an easy or gentle twisting of the handle 4 will raise the locking bar 8, not suddenly or violently, but easily and quietly, and the door will be unlocked quietly and with less noise than is true of some constructions heretofore employed for this purpose.

It will be understood that the upper and lower edges of the door may be stiffened, in the manner described, by providing hollow portions such as those shown for the vertical edges of the door, whereby the door will comprise a rectangular hollow frame with a section of sheet metal extending between the top and bottom and the sides thereof. The straight walls 7 form straight braces, and this triangular hollow formation is light and strong, and insures lightness and strength at the same time. The door is also reduced somewhat in weight by using the angle iron locking bar 8, as the bar is lighter, of course, when made of angle iron than it would be if made, for example, of channel iron or of tubing.

It will be seen that the housing for the locking bar 8 is provided with an opening 18 through which the arm 15 extends to engage the lug 14 previously mentioned. The slots 10 in the housing of the bar 8 may be of such length vertically that this bar has the desired limitation of up and down movement, and whereby the handle 4 will stand vertically as shown when the bar 8 is in its lowest position.

Thus it will be seen that the locking bar 8 is automatically raised and then dropped into locking position, when the door is closed. At such time the strike pieces 11 serve as stops to limit the inward closing movement of the door, whereby the latching means or locking means serve also as the means to limit the closing movement of the door. A part of the locking means are in one of the triangular and tubular reinforcing portions with which the door is provided, as shown and described, so that this triangular and tubular portion has the double function of stiffening this edge of the door and containing certain operative parts, in this particular case the vertically movable locking bar.

Thus the walls 7 form flat oblique brace walls, each brace extending obliquely from the edge of the wall 16 to the back of the wall 5, whereby a very stiff and strong reinforcement is provided for the edge portion of the door, in the manner shown and described. In addition, the oblique brace 7 shown at the right in Fig. 4 has the further function of enclosing the vertically movable locking bar 8, in the manner shown and described, and this bar has lateral support at

each side thereof, upon the inner surface of the chamber in which it is fully enclosed, in the manner shown and described.

What I claim as my invention is:

1. In a locker, the combination of a door, a vertically movable locking bar fully enclosed by the door and thereby having lateral support at all sides thereof and mounted to gravitate into its lower position, catch means co-operating with said bar to latch the door in closed position, adapted automatically to raise said bar and then allow it to drop into locking position when the door is closed, a rotary handle on the door operative on a pivot extending through the door, and means operative about the axis of the handle and whereby rotation of the handle will raise the bar to unlock the door, use of the handle being unnecessary to close the door.

2. A structure as specified in claim 1, said locking bar being of angle iron formation in horizontal cross section, and there being a housing for said locking bar, which housing is triangular in horizontal cross section.

3. A structure as specified in claim 1, said locking bar being carried by the door, and said means whereby said handle is operated to raise said locking bar comprising a lug on the locking bar and an arm rigid with the handle and having a notch to engage said lug.

4. A structure as specified in claim 1, said means for co-operating with the locking bar to latch the door in closed position comprising one or more double angle strike pieces and one or more hook-like engaging portions rigid with said locking bar to engage said one or more strike pieces.

5. In a locker, the combination of a casing, and a swinging door therefor, said door comprising sheet metal bent at edges thereof to provide hollow stiffening portions which are triangular in cross section, so that each portion is triangular and tubular in cross section, the metal being bent around inwardly and back upon itself, whereby a flat brace wall is formed at an oblique angle between the front wall and the inner edge of the door, said brace forming a bevel for the inner side of each tubular portion, operative latching parts enclosed in one tubular portion and means on the locker to cooperate with said latching parts when the door is closed.

6. The improved locking means for a locker, comprising a vertically movable locking bar enclosed in the edge portion of the locker door, whereby the bar has lateral support at all sides thereof on the inner surface of the enclosing chamber, and means whereby said bar is automatically raised and then dropped into locking position, when the door is closed, substantially as shown and described.

7. In a locker, means forming the body of

- the locker, a swinging door having one edge hinged thereon, having its other edge formed with a vertically disposed guide, a locking bar carried in said guide portion of the door, the guide enclosing and thereby holding the bar against lateral displacement in any direction, forming a stiff tubular door edge whereby said bar has lateral support for each side thereof, means for raising and lowering said locking bar, stop means for limiting the closing movement of the door, and means on said locking bar to engage said stop means, adapted automatically to raise the bar and then allow it to drop into locking position, when the door is closed, together with means to connect said stop means rigidly to the inside of said body.
8. A structure as specified in claim 7, said stop means comprising a strike piece with a slot therein, said slot being in a plane parallel with the front of the locker, and said means on the locking bar for engaging the stop means comprising a portion with a beveled edge to engage the lower end of said slot, thereby to raise the locking bar, 25 and having a notch to hook over the lower edge of the slot to lock the door in closed position.
9. A structure as specified in claim 7, said stop means comprising a plurality of double angle strike pieces, each strike piece provided with a slot, and said engaging means on the locking bar comprising projections extending parallel with the side of the locker, when the door is closed, adapted to 30 extend through said slots and to engage the lower edge of each slot to lock the door in closed position.
8. A structure as specified in claim 7, said stop means comprising a strike piece with a slot therein, said slot being in a plane

Signed

GRAHAM H. PIGGOT.
